FIRE CONTROL MECHANISM

Alonzo F. Gaidos, Redwood City, Calif., assignor
to the United States of America as represented
by the Secretary of War

Application September 3, 1946, Serial No. 694,443

6 Claims. (Cl. 89—140)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a fire control mechanism for firearms, more particularly to a fire control mechanism having a sliding sear to effect semi-automatic or full automatic fire control.

Fire control mechanisms for automatic firearms are generally highly complicated mechanisms. Such mechanisms contain a large number of parts which are difficult to manufacture and likewise hard to assemble to the firearm. Still another drawback to most fire control mechanisms is the difficulty of obtaining a satisfactory trigger pull.

Accordingly, it is an object of this invention to provide an improved fire control mechanism having both semi-automatic and full automatic fire control.

Another object of this invention is to provide a fire control mechanism for a firearm having a sliding sear permitting semi-automatic and full automatic fire control.

Still another object of this invention is to provide a fire control mechanism having both semi-automatic and full automatic fire control for any firearm having a recoiling breech member.

Another object of this invention is to provide a fire control mechanism for a firearm wherein full automatic fire is obtained from the open bolt position and wherein semi-automatic fire is obtained from the closed bolt position.

The specific nature of the invention as well as other objects and advantages thereof will clearly appear from a description of a preferred embodiment as shown in the accompanying drawings in which:

Fig. 1 is a fragmentary longitudinal sectional view of a firearm showing the fire control mechanism in the semi-automatic position with the bolt closed prior to releasing the trigger;

Fig. 2 is a view similar to Fig. 1 but shown in the full automatic position with the bolt retracted;

Fig. 3 is a detail view in longitudinal section of the fire control mechanism shown set for full automatic fire and after the trigger has been pulled rearwardly;

Fig. 4 is a view similar to Fig. 3 showing the trigger blocked by the safety;

Fig. 5 is a front end view of the fire control mechanism with the housing broken away to show the arrangement of the sear when positioned for semi-automatic fire;

2

Fig. 6 is an enlarged detail view of the sear shown in longitudinal section;

Fig. 7 is an enlarged detail perspective view of the pawl;

Fig. 8 is an enlarged detail side elevational view of the safety;

Fig. 9 is an enlarged detail view of the safety handle;

Fig. 10 is an enlarged detail perspective view of the trigger; and

Fig. 11 is a bottom plan view of the actuator showing the lugs for full automatic fire and semi-automatic fire.

In Fig. 1 there is shewn in assembled relation 15 the fire control mechanism embodying this invention. Such mechanism is contained within a trigger guard housing 1 and comprises mainly a trigger 2, a sear 3 and a pawl 4.

Trigger 2 (Fig. 10) is provided with a conventional curved portion 5 for engagement thereof by the finger of the operator. A transverse hole 6 is provided at the top of trigger 2 for pivotally mounting such trigger on a transverse pin in trigger guard housing 1. A rearwardly projecting lug 8 is provided on trigger 2. The upper surface of such lug is horizontally disposed as shown at 9 and a flat-leaf type spring 10 rests thereon to bias trigger 2 in a counterclockwise direction as shown in Figs. 1 and 2. Leaf spring 10 is secured to trigger guard housing 1 by a screw 11. A transverse lug 12 is provided on the forward part of trigger 2 in alignment with hole 6. Substantially one-half of transverse lug 12 is of reduced width thereby providing two forwardly projecting lugs 13 and 14, the lug 13 being of narrower width than lug 14. The forward edges of such lugs are bevelled as shown at 15.

Sear 3 comprises essentially two arms 16 and 17 disposed at an acute angle as shown in Figs. 1, 2, 3, 4 and 6. A transverse hole 18 is provided at the juncture of arms 16 and 17 for mounting sear 3 on a transverse pin 19 provided with an integral head 19'. Such pin is transversely mounted in trigger guard housing 1 which is on the upper forward portion thereof.

On the other end of pin 19, a head portion 20 (Fig. 5) is secured by a suitable transverse pin 20' and this is provided to facilitate sliding sear 3 transversely with respect to housing 1, as will be later described. The apex of sear 3 formed by the juncture of arms 16 and 17 is bifurcated as shown at 21. Such bifurcation is somewhat deeper than hole 18 and is provided to permit mounting a torsion spring 22 on pin 19 to bias sear 3 upwardly.

The lower end portion 23 of arm 17 is arcuately formed and a transverse hole 24 is provided in such end portion, the latter being bifurcated as shown at 25 to permit mounting pawl 4 therein as will be presently described. The extreme end of arm 16 is provided with a substantially squared end surface 26 so that such surface can engage a sear notch in a recoiling member of a firearm as will be later explained.

A cylindrical recess 27 is provided in the bottom of bifurcation 25 in which is placed a spring 28 which bears against pawl 4. Pawl 4 is a substantially L-shaped member as shown in Fig. 7 and its upright arm is of reduced thickness to permit such to be inserted within the bifurcation 25, as shown. A transverse hole 29 provided in pawl 4 permits such pawl to be pivotally secured to arm 17 of sear 3 by transverse pin 30 which is inserted through hole 24 of arm 17 and hole 29 of pawl 4. A cylindrical recess 31 in the horizontal arm of pawl 4 receives the other end of spring 28 contained in the recess 27 of sear 3.

Thus spring 28 is adapted to bias pawl 4 in a counterclockwise direction. The movement of pawl 4, however, is limited by the end 32 of the upright arm of pawl 4 which, as stated, contacts the bottom of bifurcation 25 in sear 3. The extreme end of the horizontal arm of pawl 4 is arcuately formed as shown at 33, for a purpose which will be presently explained.

The arm 16 projects upwardly through trigger guard housing 1 as shown in Fig. 1, to engage an actuator 34 of a firearm which is generally indicated by the numeral 35, as will be later described. The upward movement of sear 3 is limited by the forward portion of arm 16 and said forward portion strikes the top of trigger guard housing 1 in such a way as to limit the upward movement of sear 3.

It is to be understood that the fire control mechanism herein described may be utilized by any firearms having a recoiling breech member. One of such firearms is illustrated in Fig. 1 and comprises mainly a receiver 36 in which the actuator 34 is slidably contained in any conventional manner. A firearm bolt 37 is likewise slidably mounted in suitable ways (not shown) directly above actuator 34. Connection between bolt 37 and actuator 34 is made by integral lug 38 provided on actuator 34 adapted to enter a suitable locking cam slot 37' provided on the underside of bolt 37.

A firing pin 40 is provided in a suitable axial recess 41 in bolt 37. Lug 38 of actuator 34 engages two oppositely disposed shoulders 42 which are provided on firing pin 40 formed by a suitable transverse slot 42'. Such engagement is provided to cock firing pin 40.

A spring 43 surrounding firing pin 40 biases it forwardly to discharge a cartridge in firearm 35. One end of a driving spring 44 is contained within an axial recess 45 provided in actuator 34. A driving-spring-guide rod 46, provided to support spring 44, has one end removably secured to a buffer mechanism indicated generally by numeral 47 as shown in Fig. 2 while the other end of spring 44 abuts the forward face of axial recess 45 of actuator 34.

On the bottom surface of actuator 34 there is provided an integral transverse lug 49 having a sloped forward surface 50 for engagement therewith by surface 26 of sear 3. Lug 49 is positioned near the forward end of actuator 34 and extends approximately halfway across such actuator as shown in Fig. 11. There is a transverse lug 51

on the extreme rear end of actuator 34 and a sloped surface 52 is provided on the forward face thereof which is engaged by surface 26 for semi-automatic fire as will be later described.

The fire control mechanism herein described is readily set for semi-automatic fire when sear 3 is moved transversely with respect to housing 1 by hand portion 20 of pin 19 so that pawl 4 is opposite lug 13 of trigger 2. The firearm bolt 37 is manually retracted in order to cock firing pin 40.

Such cocked position is shown in Fig. 1 and in such position arm 16 of sear 3 is raised upwardly as shown so that surface 26 thereof engages sloped surface 52 of transverse lug 51 provided on actuator 34. With the actuator 34 held in such retracted position, lug 38 maintains firing pin 40 retracted in a cocked position and against the bias of spring 43. Trigger 2 is pulled rearwardly to release actuator 34 thereby rotating bolt 37 by the movement of lug 38 through cam slot 37' to permit firing pin 40 to be biased forwardly by spring 43.

Lug 13 on trigger 2, which is in engagement with arcuate surface 33 of pawl 4, then rotates sear 3 in a counterclockwise direction about pin 19. Such movement then disengages surface 26 of sear 3 from contact with surface 52 of lug 51 thereby permitting the actuator 34 and firing pin 40 to be biased forwardly to effect discharge of a cartridge. Continued pressure on trigger 2 causes further rotation of the sear 3 so that lug 13 slips off the end of pawl 4, whereupon sear 3 is immediately biased upwardly by torsion spring 22 with the result that arm 16 is immediately raised into the path of lug 51 on the extreme rear end of actuator 34. Thus sear 3 will engage actuator member 34 to cock firing pin 40 before the bolt has fully closed.

Lug 38 of actuator 34 holds the bolt 37 and actuator 34 in locked relationship prior to the release of sear 3 as shown in Fig. 1. Cam slot 37' of bolt 37 has a cam shoulder which engages lug 38 of actuator 34. When actuator 34 is released from the position as shown in Fig. 1, the bias of the driving spring 44 urges actuator 34 forwardly rotating bolt 37 a partial turn to a locked battery position. Lug 38 of actuator 34 then carries the firing pin 40 forwardly to the firing position.

According to the preferred form of the invention, the sear 3 can not be disengaged from lug 51 until pressure of trigger 2 has been released. Thus a flat spring 10 is provided to bias trigger 2 forwardly so that lug 13 will pivot pawl 4 upwardly about pin 30 against the bias of spring 28 whereby lug 13 can again rest on arcuate surface 33 of pawl 4 and trigger 2 will again be in position to effect release of sear 3 from actuator 34. It is desired to point out that when pressure is applied to trigger 2, pawl 4 can rotate in only one direction. Such is effected by end 32 of pawl 4 contacting the bottom bifurcation 25 thereby permitting only rotation of pawl 4 in a counterclockwise direction as shown in Figs. 1, 2, 3, and 4.

To obtain full automatic fire, sear 3 is moved transversely with respect to housing 1 by the member 20 to bring pawl 4 opposite lug 14 as shown in Fig. 3. In such position of the sear, only engagement of lug 49 by the sear to obtain automatic fire is possible and lug 51 is utilized only for semi-automatic fire from the closed bolt position. As automatic firing is obtained from the open bolt position, bolt 37 is manually retracted 75 to open position whereupon surface 26 of sear 3

engages sloped surface 50 of lug 49 provided on the underside of actuator 34 so as to hold actuator 34 and hence bolt 37 in the retracted position.

Thereupon actuator 34 is released to permit it, as well as bolt 37, to go forwardly to discharge a cartridge when trigger 2 is pulled rearwardly. A rearward pull on trigger 2 rotates sear 3 in a counterclockwise direction as lug 14 rests on top of the arcuate surface 33 of pawl 4, thus end 26 of sear 3 is rotated out of contact with sloped surface 50 of lug 49 thereby releasing actuator 34 and permitting both actuator and bolt to be biased forwardly by driving spring 44 to effect discharge of the firearm.

In the full automatic position, lug 14 is at all times maintained on top of arcuate surface 33 of pawl 4, hence when trigger 2 is pulled rearwardly, surface 26 of sear 3 is maintained out of contact with sloped surface 50 of lug 49 on actuator 34. Thus the firearm will continue to fire automatically as long as trigger 2 is held rearwardly or until the cartridges contained in the magazine or belt are exhausted. Release of trigger 2 permits torsion spring 22 to immediately bias sear 3 upwardly into the path of lug 49 to hold actuator 34 and hence bolt 37 in the retracted or open position.

Trigger 2 is conveniently blocked by a safety 53 to prevent discharge of the firearm. Such safety is transversely mounted in guard housing 1 and comprises a pin 54 provided with flattened ends as shown at 55 in Fig. 8. A handle 56, shown in Fig. 9, may be mounted on either of such flattened ends. A transverse slot 57 is provided centrally on pin 54 to permit trigger 2 to be pulled rearwardly when such slot is aligned with the rear of such trigger by handle 56. Trigger 2 is blocked when such slot is rotated away from the trigger. A suitable detent 58 is provided to yieldingly secure safety 53 in either the safe or ready position.

From the foregoing description it is therefore readily apparent that there is hereby provided a simple, easily constructed fire control mechanism for a firearm that will provide full automatic fire from an open bolt position or semi-automatic fire from a closed bolt. Such mechanism is positive in operation and will provide a somewhat positive sear release.

I claim:

1. The combination in an automatic firearm having a reciprocating breech member movable between a battery position and a recoil position of, an actuator engaging the breech member, a sear pivotally mounted on the firearm having means for selectively moving said sear transversely with respect to the firearm to either of two spaced positions, first means on said actuator engageable by said sear when in one of said two positions whereby semi-automatic fire is obtained when the breech member is in battery position, and second means on said actuator engageable by said sear when in the other of said spaced positions whereby full automatic fire is obtained from the recoil position of the breech member.

2. The combination in an automatic firearm having a reciprocating breech member movable between a battery position and a recoil position of a firing pin mounted for limited longitudinal movement within the breech member, said firing pin having a transverse slot thereon, an actuating member engaging said slot, resilient means associated with said actuating member and the breech member adapted to bias the same to battery posi-

tion, and a sear pivotally mounted on the firearm having means for selectively positioning said sear transversely with respect to the firearm to either of two spaced positions, all adapted and arranged whereby when said sear is engaged in one of said two spaced positions with said actuating member with the breech member in the battery position said actuating member and said firing pin are held retracted until release of said sear and whereby semi-automatic fire is obtained and whereby when said sear is in the other of said spaced positions, the said actuating member and the breech member are held in the recoil position until release of said sear whereby automatic fire is obtained.

3. The combination defined in claim 1 wherein said first means comprises a first transverse sear engaging projection provided on the rear portion of said actuator and wherein said second means comprises a second transverse sear engaging projection provided on the forward portion of said actuator, the second-named projection extending only halfway across said actuator so that when said sear is positioned for automatic fire said sear engages said second-named projection.

4. A fire control mechanism for an automatic firearm having a receiver comprising, a trigger pivotally mounted on the receiver, a sear pivotally mounted on the receiver, means for selectively positioning said sear transversely with respect to the firearm in either of two spaced positions, and a pawl pivotally mounted on said sear engageable by said trigger in one of said spaced positions of said sear to effect release of said sear to obtain semi-automatic fire and whereby automatic fire is obtained when said sear is moved to the other of said spaced positions.

5. A fire control mechanism for an automatic firearm having a receiver comprising a trigger pivotally mounted on the receiver, said trigger having a first and a second sloped transverse lug thereon, said second lug being substantially longer than said first lug, a sear pivotally mounted on the receiver, means for selectively positioning said sear transversely with respect to the firearm in either of two spaced positions, a pawl pivotally mounted on said sear, said pawl normally engaging the underside of either of said first or second lugs depending on the spaced position of said sear, resilient means urging the pivoted end of said pawl into contact with said sear, said sear being arranged for semi-automatic fire when moved to one of said spaced positions whereby said pawl lies underneath said first lug and whereby automatic fire is obtained when said sear is moved to the other of said spaced position to position said pawl underneath said second lug.

6. A fire control mechanism for an automatic firearm having a receiver comprising a trigger pivotally mounted on the receiver, said trigger having a first and a second sloped transverse lug thereon, said second lug being substantially longer than said first lug, a sear pivotally mounted on the receiver, means for selectively positioning said sear transversely with respect to the firearm in either of two spaced positions, a pawl pivotally mounted on said sear, said pawl normally engaging the underside of either of said first or second lugs depending on the spaced position of said sear, resilient means urging the pivoted end of said pawl into contact with said sear, said pawl being engageable with the underside of said first lug when said sear is moved to one of said two spaced positions whereby release of said trigger rotates said pawl to effect release of said sear, said pawl

being arranged to slip over the end of said first lug after release of said sear to permit said sear to rotate to its normal engaging position, said pawl being biased into contact with said sear by said resilient means upon release of said trigger whereby semi-automatic fire is obtained, and whereby automatic fire is obtained when said sear is moved to the other of said spaced positions, said pawl then being engageable with the

underside of said second lug whereupon release of said trigger rotates said pawl to effect release of said sear, said second lug being adapted to maintain engagement of said pawl in the pulled position of said trigger.
